United States Patent Office

Des. 186,133

Patented Sept. 15, 1959

186,133

FORMER FOR PACKAGING MACHINE

William C. Leisure, Houston, Tex., assignor to Mira-Pak, Inc., Houston, Tex., a corporation of Texas

Application March 14, 1958, Serial No. 50,034

Term of patent 14 years

(Cl. D55—1)

Fig. 1 is a perspective view of a former for packaging machine showing my new design;

Fig. 2 is a side elevational view thereof;

Fig. 3 is a top plan view; and

Fig. 4 is a front elevational view thereof.

I claim:

The ornamental design for a former for packaging machine, substantially as shown.
